UNITED STATES PATENT OFFICE

DUDLEY D. LEVY, OF NEW YORK, N. Y., ASSIGNOR TO DUDLEY RESEARCH CORPORATION, OF NEW YORK, N. Y., A CORPORATION OF NEW YORK

VACUUM TANK

Application filed December 29, 1927. Serial No. 243,363.

This invention relates to valve construction for tanks and in particular for vacuum tanks.

The object of my invention includes the provision of a simple but reliable and efficient construction whereby a certain reserve supply of liquid is always assured in the tank and a new supply of liquid is added when the reserve supply has dropped to a predetermined level.

Another object includes the provision of a liquid supply valve construction of few parts for controlling the liquid supply. I also provide a simple liquid equalizing valve and means to operate said valve in unison with the supply valve.

Other objects will appear hereinafter and I obtain these objects by the construction shown in the accompanying drawings in which—

Figure 1 is a view, partly in section, of a tank to which my invention is applied;

Fig. 2 is a view taken on the line 2—2 looking in the direction of the arrows, but showing in dotted lines the relative location of the liquid equalizing valve and the liquid outlet in the partition and in the bottom of the tank; and

Fig. 3 is a view showing the liquid supply valve and the liquid equalizing valve in opposite positions from that shown in Fig. 1, that is, the former valve is in closed position.

The same numerals of reference refer to like parts in the several views.

Referring now to the accompanying drawings wherein I have shown a preferred form of construction, but to which I do not wish to be understood as having limited myself except as set forth in the appended claims. I provide a closed tank 10 which is divided by a partition 11 into an upper or liquid supply chamber 12 and a lower liquid reservoir or constant feed chamber 13. The partition 11 is provided with a port 14 which is closed by a valve 15 in the manner described more fully below.

The upper or liquid supply chamber 12 is provided with three bores through the outer wall thereof; bore 16 is, in practice, connected to a liquid supply (not shown). Bore 17 is

suitably connected to an exhaust or suction device (not shown) and bore 18 opens to the atmosphere. These bores are properly located so as to be controlled by the boot-like end 19 of the liquid supply valve 20 when said valve is caused to oscillate on pivot 21 between stops 22 and 23. A float 24 is supported on a pivot 25 by arm 26. This arm has an extension 27 on which is fastened one end of spring 28. The other end of spring 28 is fastened at 29 to the leg of valve 20. It will be observed that the point 29 swings about the pivot point 25 as the float lowers or rises due to the fall and rise of the liquid in the tank. In the position shown in Fig. 1 the suction port 17 and the liquid supplying port 16 are closed by valve member 20. If now the level of the liquid falls and lowers the float arm, extension 27 will swing towards and over the pivot point 21 until the tension of spring 28 snaps over the valve 20 into liquid supplying position (shown in Fig. 3). Ports 16 and 17 are now uncovered while port 18 is closed and liquid flows into the upper or supply chamber.

When valve 20 snaps into the liquid supplying position spring 30, which connects point 29 with stem 31 on the valves 20 and 15 respectively, is put under tension sufficient to close valve 15, which causes the liquid level 80 in the supply tank to rise. As the float rises it also moves the arm extension 27 to the liquid cut-off position (shown in Fig. 1) and thus closes the liquid supply and the exhaust ports. When this happens the tension on spring 30 is decreased and valve 15 opens and permits the liquid in the supply tank to replenish the liquid supply in the reservoir 13. An outlet 40 at any suitable position in the bottom of the reservoir affords means for connecting a liquid conducting tube (not shown) to place of use, as for example to a carburetor.

A suitable pipe 41 open to the atmosphere equalizes the pressure on the liquid within the reservoir. Thus for example when the equalizing valve 15 is shut and liquid is to be withdrawn from the reservoir, air is freely admitted through pipe 41 to replace the liquid. When on the other hand, the equaliz-

ing valve is opened to replenish the liquid supply in the reservoir from the supply chamber the air within the reservoir will be exhausted through pipe 41 to the extent that a 5 constant pressure is maintained on the enclosed liquid, namely, that of the atmosphere. It will be apparent, therefore, that by my construction a liquid supply is maintained under constant pressure within the reservoir 10 and that the mechanism within the liquid supplying chamber 12 operates intermittently to replenish said reservoir as and when needed. At the same time the liquid is free to flow from a reservoir through the liquid outlet as it is needed and this flow is substantially at a constant pressure.

Having now described my invention, what I claim as new and useful and desire to secure by Letters Patent is:

20 1. In a liquid supplying tank, a partition to divide said tank into a liquid receiving chamber and a liquid storing chamber, a valve in said partition for maintaining a constant liquid supply in said storing chamber, said receiving chamber having an air port, a suction port and a liquid supply port extending through the walls of said chamber and a valve in said receiving chamber to cover and uncover said ports for intermittently replenishing the liquid in said tank.

25 2. In a liquid supplying tank, a partition to divide said tank into a liquid receiving chamber and a liquid storing chamber, a valve including a hinged member on said partition, said receiving chamber having an air port, a suction port and a liquid supply port, a valve in said receiving chamber to cover and uncover said ports for intermittently replenishing the liquid in said tank, and means for 30 closing the first mentioned valve when the liquid supply and suction ports are opened.

35 3. A vacuum tank comprising a liquid supply chamber having a liquid supply port, an air port and an exhaust port, in combination with an L-shaped valve member pivotally mounted adjacent said ports and serving to selectively cover and uncover said ports, and means to actuate said valve, including a float and a resilient member, as the 40 float rises and falls.

45 4. A vacuum tank comprising a liquid supply chamber having a liquid supply port, an air port and an exhaust port, in combination with an L-shaped valve member pivotally mounted adjacent said ports and serving to selectively cover and uncover said ports, means to operate said L-shaped valve member 50 for covering and uncovering said ports, a second valve and a resilient connection between said valves whereby said second valve is closed and opened in response to oscillations of said port controlling valve.

55 5. In a liquid supplying tank, a partition to divide said tank into a liquid receiving chamber and a liquid storing chamber, a

hinged flap valve in said partition, said receiving chamber having a liquid supplying port, an air port and a suction port, a valve member for selectively controlling said ports, a resilient member connecting said port controlling valve and said hinged flap valve and means for opening the flap valve when said liquid supplying and suction ports are closed.

6. In a liquid supplying tank, a partition to divide said tank into a liquid receiving chamber and a liquid storing chamber, a flap serving as a valve hinged on said partition, said receiving chamber having a liquid supplying port, an air port and a suction port and a valve member for selectively covering or uncovering said ports and means controlled by said valve member for opening said flap.

7. In a vacuum tank, a partition to divide said tank into a liquid receiving chamber and a liquid storing chamber, a valve in said partition for maintaining a constant liquid supply in said storing chamber, means for venting said storing chamber, said receiving chamber having an air port and liquid supply and suction ports, and a boot-shaped valve to alternately cover said air port and said liquid supply and suction ports with what corresponds to the heel and entire foot portions thereof, respectively, to intermittently open said ports to maintain the level of the liquid in the receiving chamber constant.

8. In a vacuum tank, a partition to divide said tank into a liquid receiving chamber and a liquid storing chamber, a valve in said partition for maintaining a constant liquid supply in said storing chamber, means for venting said storing chamber, said receiving chamber having an air port and liquid supply and suction ports, a boot-shaped valve to alternately cover said air port and said liquid supply and suction ports with what corresponds to the heel and entire foot portions thereof, respectively, to intermittently open 100 said ports to maintain the level of the liquid in the receiving chamber constant, and means connecting the valve of said partition with the boot-shaped valve so that the valve in the partition is open while the air port is open and the liquid supply and suction ports are 105 closed and the partition valve is closed while the air port is closed and the liquid supply and suction ports are open.

110 In testimony whereof I have hereunto set my hand on this 28th day of December, A. D., 1927.

DUDLEY D. LEVY.
